CLAIM

The ornamental design for a bucket hook with tether hole as
shown and described.

DESCRIPTION

FIG. 1 is a top perspective view illustrating the bucket hook
with tether hole;

FIG. 2 is a bottom plan view of the design depicted in FIG.
1;

FIG. 3 is a first side view of the design depicted in FIG. 1;
FIG. 4 is a second side view of the design depicted in FIG.
1;

FIG. 5 is a first end view of the design depicted in FIG. 1;
FIG. 6 is a second end view of the design depicted in FIG.
1;

FIG. 7 is a top isometric view of the design depicted in FIG.
1;

FIG. 8 is bottom isometric view of the design depicted in
FIG. 1; and,

FIG. 9 is another top perspective view of the design depicted
in FIG. 1.
